UNITED STATES PATENT OFFICE.

GEORGE A. GRAY, JR., OF CINCINNATI, OHIO.

BENCH-VISE.

Specification of Letters Patent No. 26,266, dated November 29, 1859.

To all whom it may concern:

Be it known that I, GEORGE A. GRAY, Junior, of Cincinnati, Hamilton county, Ohio, have invented a certain new and useful 5 Improvement in Bench-Vises; and I hereby declare the following to be a full, clear, and exact description of the same, reference being had to the accompanying drawings, making part of this specification.

10 The invention consists in a provision whereby the workman is enabled greatly to increase the grip or bite of the jaws.

Figure 1 is a side view of a bench vise embodying my improvement. Fig. 2 is an 15 axial section through the upper screw. Fig. 3 is a perspective view of a portion of the upper screw.

A *a*, is the fixed jaw and shank. The jaw and shank *B b*, are adapted for a parallel 20 motion to and from the fixed jaw by means of the familiar appliance of two screws *C*, *D*, connected by an endless chain *E*. A cylindrical projection *C'* from the front end of the screw *C* is grooved (*c*) around its 25 periphery to receive a pin *e*, which projecting inwardly from a hollow movable head *F* confines said head while permitting its rotation upon said projection. The movable head has a customary handle *G*.

30 *H* is a spring catch—which at a certain point in the rotation of the head *F*, enters of itself a socket *h* in the screw *C*. The

portions of the screws which are within movable jaws are made slightly crowning.

Operation: A "grip" having been taken 35 in the ordinary way, the operator while still grasping the handle with his right hand withdraws the catch *H* with his left and instantly reverses the handle *G*. In this movement the upper screw *C* remaining 40 perfectly quiescent becomes a fulcrum for the jaw *B b* which now acting as a lever, has its upper end *B* powerfully pressed inward, by the retrograde motion of the lower screws *D*. By these means the customary 45 screws *D* (heretofore employed only to preserve parallelism) becomes powerfully effective for an increased grip of the jaws, the action being performed by a simple reverse movement of the customary lever without 50 stooping or detention.

A vise thus constructed permits the employment of a very short manageable handle.

I claim as new and of my invention—

The described combination of the handle 55 *G* loose head *F* and catch *H* with the jaws, screws and endless chain of a parallel bench vise.

In testimony of which invention, I hereunto set my hand.

G. A. GRAY, JR.
